UNITED STATES PATENT OFFICE.

ADRIAN F. WOLFF, OF WATERBURY, CONNECTICUT, ASSIGNOR TO THE SCOVILL MANUFACTURING COMPANY, OF SAME PLACE.

DESIGN FOR AN OIL-CAN.

SPECIFICATION forming part of Design No. 27,462, dated August 3, 1897.

Application filed February 18, 1895. Serial No. 538,876. Term of patent 7 years.

To all whom it may concern:

Be it known that I, ADRIAN F. WOLFF, of Waterbury, in the county of New Haven and State of Connecticut, have invented a new 5 Design for an Oil-Can; and I do hereby declare the following, when taken in connection with the accompanying drawing and the letters of reference marked thereon, to be a full, clear, and exact description of the same, and 10 which said drawing constitutes part of this specification, and represents a view in side elevation of an oil-can embodying my design.

This invention relates to a design for an oil-can; and the design consists in the configuration of the oil-can, as shown in the accompanying illustration and hereinafter described.

As herein shown, the design consists in a flat band or fillet C, which is interposed between the convex shoulders B, formed at the upper end of the body B' of the can and the tapering neck A thereof, the said neck having the appearance of being superimposed

upon the top of the body of the can. Other features of the design are a cylindrical cap 25 D and a spout E, furnished at its base with a flange F, which overhangs the upper end of the neck; but the leading feature of the design is the flat fillet C, interposed between the convex shoulders B and the superimposed 30 neck A.

I claim—

The design herein shown and described for an oil-can consisting of a flat band or fillet interposed between convex shoulders located 35 at the upper end of the body of the can, and a tapering neck A which has the appearance of being superimposed upon the body of the can.

In testimony whereof I have signed this 40 specification in the presence of two subscribing witnesses.

ADRIAN F. WOLFF.
